UNITED STATES PATENT OFFICE.

AARON HARTZLER, OF GOSHEN, INDIANA.

STEP AND EXTENSION LADDER.

SPECIFICATION forming part of Letters Patent No. 766,246, dated August 2, 1904.

Application filed April 6, 1904. Serial No. 201,906. (No model.)

To all whom it may concern:

Be it known that I, AARON HARTZLER, a citizen of the United States, residing at the city of Goshen, county of Elkhart, State of Indiana, have invented certain new and useful Improvements in Step and Extension Ladders, of which the following is a specification.

This invention relates to improvements in combination step and extension ladders.

10 The object of this invention is to provide an improved combination step and extension ladder which may be readily adjusted as a step or as an extension ladder and which is very rigid when adjusted for either use.

15 Further objects and objects relating to structural details will definitely appear from the detailed description to follow.

20 I accomplish the objects of my invention by the devices and means described in the following specification.

The invention is clearly defined, and pointed out in the claims.

25 A structure embodying the features of my invention is clearly illustrated in the accompanying drawings, forming a part of this specification, in which—

Figure 1 is a side elevation view of my improved combination step and extension ladder adjusted as an extension-ladder. Fig. 2 is a detail longitudinal sectional view taken on a line corresponding to line 2 2 of Fig. 1. Fig. 3 is a detail longitudinal sectional view corresponding to that of Fig. 2 with the ladder adjusted as a step-ladder or trestle. Fig. 4 is an enlarged detail elevation view showing the details of one of the brackets B. Fig. 5 is an enlarged detail elevation view showing one of the brackets or plates g, adapted to coact with the bracket B in connecting the sections. Fig. 6 is a detail cross-sectional view taken on a line corresponding to line 6 6 of Fig. 4. Fig. 7 is an enlarged detail elevation view showing one of the brackets or plates f. Fig. 8 is an enlarged detail elevation view 45 of one of the supporting-brackets C" for the pivoted hooks C.

In the drawings the sectional views are taken looking in the direction of the little arrows at the ends of the section-lines, and simi-

lar letters of reference refer to similar parts throughout the several views.

Referring to the drawings, the front and rear sections A A' are made up of the usual side bars or rails provided with suitable rounds. The front section A is narrower than the rear section A', so that when collapsed 55 the front section rests between the side bars or rails of the rear section.

Secured to the inside of the side bars of the rear section at their upper ends are brackets B. These brackets B are provided with inwardly-projecting flanges B' at their forward edge, which are deflected outwardly at the bottom, as b. These brackets or plates are also provided with inwardly-projecting rib-like flanges B'', which are adapted to engage the ends of the side bars of the section A when the same is adjusted as a trestle or step-ladder. The brackets B are also provided with key-shaped grooves E on their inner 60 faces. These grooves E are adapted to receive the projecting pins g' of the plates g, which are arranged on the outer faces of the side bars of the front section. Thus arranged when the structure is adjusted as a step-ladder 65 or trestle the pins g' engage the key-shaped slots and the projecting ribs on the brackets engage the ends of the ladder, as before described, thereby locking the same and rigidly supporting the sections in their extended position.

The inner faces of the side bars of the rear section are provided with longitudinal grooves F. The grooves F are provided with a transverse opening F' toward their lower ends. 70 The side bars or front section are provided with outwardly-projecting pins f, which are adapted to engage these grooves when the sections are collapsed for adjusting as an extension-ladder.

90 Supporting-hooks C, which are adapted to engage the rounds on the rear section A', are carried by the front section A. These supporting-hooks are pivotally supported on suitable brackets C'', which are secured on the inner faces of the side bars or rails of the front section A toward their lower ends. The brackets are provided with inwardly-

projecting pins *d* to receive the hooks *C*. Springs *e* are provided for holding the hooks normally inward. These springs are carried by suitable inwardly-projecting pins *d'* on 5 the brackets *c''*. The hooks *C* are provided with inwardly-projecting pivoted guards *c*, which are adapted to prevent the engagement of the hooks with the rounds when the front section is moved downwardly on the rear section. 10 The guards *c* are provided with counter-weights *c'*. The hooks *C* are provided with hand-pieces *C'* for convenience in releasing. Suitable loops *D* are provided to limit the movement of the hooks and assist in retaining 15 them in position.

With the parts thus arranged when it is desired to use the structure as an extension-ladder the sections may be closed together, so that the section *A* rests upon the section 20 *A'*, with the pins *f* in engagement with the groove *F*. The section *A* may then be moved upwardly to the desired point. The hooks *C*, which are held inwardly by the spring, slide over the rounds and engage the same. 25

As the upper end of the ladder slides between the ribs of the brackets *B*, the parts are very securely retained together when adjusted in this position. If it is desired to adjust the same as a step-ladder or trestle, the 30 hooks are released and the section *A'* is free to slide down and be swung out. In this movement the guards *c* guard the hooks, so that they do not engage with the rounds. As before remarked, when the ladder is adjusted 35 as an extension-ladder the upper ends of the side bars of the section *A* are engaged by the ribs on the plates or brackets *B*, so that they are securely and rigidly supported. It is evident from the foregoing description that the 40 parts of my improved ladder are very economical to produce and readily assembled.

I have illustrated and described my improved step and extension ladder in detail in the form preferred by me. I am, however, 45 aware that it is capable of considerable variation in structural details without departing from my invention.

Having thus described my invention, what I claim as new, and desire to secure by Letters 50 Patent, is—

1. In a combination step and extension ladder, the combination of front and rear sections, said front section being adapted to rest between the side bars of the rear section when 55 collapsed together; brackets *B*, having inwardly-projecting flanges or ribs *B' B''* thereon and key-shaped grooves *E* therein, arranged at the top of said rear section; outwardly-projecting pins on said front section adapted to engage said grooves *E*; longitudinal grooves in the inner faces of the side bars of said rear section; outwardly-projecting pins on said front section, arranged at the lower end thereof, adapted to engage said grooves when said

sections are collapsed together; hooks *C* having outwardly-projecting finger-pieces *C'*; pivoted guards *c* for said hooks; brackets to which said hooks are pivotally secured carried by said front section; springs carried by said brackets adapted to hold said hooks normally 65 inward; and loops *D* adapted to embrace the finger-pieces *C'* of said hooks, to serve as stops therefor, all coacting for the purpose specified. 70

2. In a combination step and extension ladder, the combination of front and rear sections, 75 said front section being adapted to rest between the side bars of the rear section when collapsed together; brackets *B* having inwardly-projecting flanges or ribs *B' B''* thereon and key-shaped grooves *E* therein, arranged at the top of said rear section; outwardly-projecting pins on said front section adapted to engage said grooves *E*; longitudinal grooves in the inner faces of the side bars of said rear section; outwardly-projecting pins on said 80 front section, arranged at the lower end thereof, adapted to engage said grooves when said sections are collapsed together; hooks *C* having inwardly-projecting finger-pieces *C'*; pivoted guards *c* for said hooks; brackets to which said hooks are pivotally secured, carried by said front section; springs carried by said brackets adapted to hold said hooks normally 85 inward, all coacting for the purpose specified.

3. In a combination step and extension ladder, the combination of front and rear sections, 90 said front section being adapted to rest between the side bars of the rear section when collapsed together; brackets *B*, having inwardly-projecting flanges or ribs *B' B''* thereon and key-shaped grooves *E* therein, arranged at the top of said rear section; outwardly-projecting pins on said front section adapted to engage said grooves *E*; longitudinal grooves in the inner faces of the side bars of said rear 95 section; outwardly-projecting pins on said front section, arranged at the lower end thereof, adapted to engage said grooves when said sections are collapsed together; hooks pivotally secured to said front section; pivoted 100 guards *c* for said hooks; and loops *D* adapted to embrace the finger-pieces *C'* of said hooks, to serve as stops therefor, all coacting for the purpose specified. 105

4. In a combination step and extension ladder, the combination of front and rear sections, 110 said front sections being adapted to rest between the side bars of the rear section when collapsed together; brackets *B*, having inwardly-projecting flanges or ribs *B' B''* thereon and key-shaped grooves *E* therein, arranged at the top of said rear section; outwardly-projecting pins on said front section, adapted to engage said grooves *E*; longitudinal grooves in the inner faces of the side bars of said rear 115 section; outwardly-projecting pins on said front section, arranged at the lower end thereof, adapted to engage said grooves when said 120 sections are collapsed together; hooks pivotally secured to said front section; pivoted guards *c* for said hooks; and loops *D* adapted to embrace the finger-pieces *C'* of said hooks, to serve as stops therefor, all coacting for the purpose specified. 125

- sections are collapsed together; hooks C having outwardly-projecting finger-pieces C'; brackets to which said hooks are pivotally secured, carried by said front section; springs carried by said brackets adapted to hold said hooks normally inward; and loops D adapted to embrace the finger-pieces C' of said hooks, to serve as stops therefor, all coacting for the purpose specified.
- 5 5. In a combination step and extension ladder, the combination of front and rear sections, said front section being adapted to rest between the side bars of the rear section when collapsed together; brackets B, having inwardly-projecting flanges or ribs B' B'' thereon and key-shaped grooves E therein, arranged at the top of said rear section; outwardly-projecting pins on said front section adapted to engage said grooves E; longitudinal grooves 15 in the inner faces of the side bars of said rear section; outwardly-projecting pins on said front section, arranged at the lower end thereof, adapted to engage said grooves when said sections are collapsed together; hooks C having outwardly-projecting finger-pieces C'; brackets to which said hooks are pivotally secured, carried by said front section; and springs carried by said brackets adapted to hold said hooks normally inward, all coacting 20 for the purpose specified.
- 6 6. In a combination step and extension ladder, the combination of front and rear sections, said front section being adapted to rest between the side bars of the rear section when collapsed together; brackets B, having inwardly-projecting flanges or ribs B' B'' thereon and key-shaped grooves E therein, arranged at the top of said rear section; outwardly-projecting pins on said front section adapted to 25 engage said grooves E; longitudinal grooves in the inner faces of the side bars of said rear section; outwardly-projecting pins on said front section, arranged at the lower end thereof, adapted to engage said grooves when said sections are collapsed together; hooks pivotally secured to said front section; and loops D adapted to embrace the finger-pieces C' of said hooks, to serve as stops therefor, all coacting for the purpose specified.
- 7 7. In a combination step and extension ladder, the combination of front and rear sections, said front section being adapted to rest between the side bars of the rear section when collapsed together; brackets in which the side bars of the front sections are adapted to slide, having key-shaped grooves therein, arranged at the top of said rear section; outwardly-projecting pins on said front section adapted to engage said grooves; longitudinal grooves 35 in the inner faces of the side bars of the said rear section; outwardly-projecting pins on said front section, arranged at the lower end thereof, adapted to engage said grooves when said sections are collapsed together; and hooks pivotally secured to said front section; and pivoted guards for said hooks, for the purpose specified.
- 8 8. In a combination step and extension ladder, the combination of front and rear sections, said front section being adapted to rest between the side bars of the rear section when collapsed together; brackets in which the side bars of the front section are adapted to slide, having key-shaped grooves therein, arranged at the top of said rear section; outwardly-projecting pins on said front section, adapted 40 to engage said grooves; longitudinal grooves in the inner faces of the side bars of said rear section; outwardly-projecting pins on said front section, arranged at the lower end thereof, adapted to engage said grooves when said sections are collapsed together; hooks pivotally secured to said front section; and springs for holding said hooks normally inward, for the purpose specified.
- 9 9. In a combination step and extension ladder, the combination of front and rear sections, said front section being adapted to rest between the side bars of the rear section when collapsed together; brackets in which the side bars of the front section are adapted to slide, having key-shaped grooves therein, arranged at the top of said rear section; outwardly-projecting pins on said front section, adapted 45 to engage said grooves; longitudinal grooves in the inner faces of the side bars of said rear section; outwardly-projecting pins on said front section, arranged at the lower end thereof, adapted to engage said grooves when said sections are collapsed together; hooks pivotally secured to said front section; and pivoted guards for said hooks, for the purpose specified.
- 10 10. In a combination step and extension ladder, the combination of front and rear sections, said front section being adapted to rest between the side bars of the rear section when collapsed together; brackets in which the side bars of the front section are adapted to slide, having key-shaped grooves therein, arranged at the top of said rear section; outwardly-projecting pins on said front section, adapted 50 to engage said grooves; longitudinal grooves in the inner faces of the side bars of the said rear section; outwardly-projecting pins on said front section, arranged at the lower end thereof, adapted to engage said grooves when said sections are collapsed together; and hooks pivotally secured to said front section, for the purpose specified.
- In witness whereof I have hereunto set my hand and seal in the presence of two witnesses.
